UNITED STATES PATENT OFFICE.

WILTON E. DARROW, OF SUTTER CREEK, CALIFORNIA.

SLIME-CONCENTRATOR.

1,035,165.

Specification of Letters Patent. Patented Aug. 13, 1912.

Application filed August 21, 1908. Serial No. 449,633.

To all whom it may concern:

Be it known that I, WILTON E. DARROW, citizen of the United States, residing at Sutter Creek, county of Amador, and State of California, have invented certain new and useful Improvements in Slime-Concentrators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in concentrating apparatus more especially designed for the separation of slimes from the gangue with which they are mingled. The term slimes in this connection means the lighter and exceedingly fine metallic values whose specific gravity is not sufficient to cause them to readily stratify. In other words, they are normally held in suspension by the water and are lost with the gangue when ordinary concentrators are employed. In other words a concentrating apparatus which is adapted for the saving of the coarser mineral values is ordinarily not adapted for saving the finer and lighter values, termed slimes, as above indicated.

While my improved construction is particularly adapted for the saving of slimes as aforesaid, it may also be employed for the saving of both the slimes and the heavier and coarser values. When operated for this purpose, the movement to which the tables are subjected, being a longitudinal vibratory action, imparted by a differential mechanism, causes the slimes to stratify upon a canvas-covered top or table, while the differential movement is of such character as to cause the heavier values to travel over the extremity of the table, which I will term the head, provision being made for catching these heavier values as they leave the table proper.

In the specific construction illustrated in the drawing, are arranged a series of tables in circular form; there may be a number of gangs or sets of tables, each gang or series being arranged in one plane, and another gang or series in an upper or lower plane. In other words, the different series of tables are arranged one above another, the number of series depending upon the required capacity of the apparatus. The entire structure

carrying the tables is mounted to rotate and the launder which delivers the pulp directly to the tables, rotates with the latter, a stationary supply launder being mounted above the main launder. The launder which delivers material to the tables is continually receiving a supply from the stationary launder, but the latter is divided so that the pulp is delivered to the tables during only a portion of each circuit or complete rotation, wash water from the launder being delivered to the tables during another portion of the rotation, while during a comparatively short portion at the end of each revolution, the wash water is cut off and sprays of water are directed upon the tables, one spray being employed for the purpose of washing off the middlings and another and subsequent spray being used for removing the pure metallic values. Immediately after this is completed, the tables move under the portion of the launder which delivers pulp thereto, and the operation herefore outlined is repeated on each series of tables.

Having briefly outlined my improved construction, I will proceed to describe the same in detail, reference being made to the accompanying drawing in which is illustrated an embodiment thereof.

In this drawing, Figure 1 is a plan view of my improved concentrating apparatus looking downwardly upon the tables with the launders and other mechanism above, removed. This view may be termed a section taken on the line 1—1 Fig. 2 viewed in the direction of the arrow. Fig. 2 is a vertical section of the apparatus taken approximately on the line 2—2 Fig. 1. Fig. 3 is a fragmentary view showing a portion of the structure illustrated in Fig. 2 but on a larger scale. This view illustrates more particularly the means for imparting the differential reciprocating or vibratory movement to the different series of tables. Fig. 4 is a top plan view of the initial launder employed in connection with my improved apparatus.

The same reference characters indicate the same parts in all the views.

Let the numeral 5 designate a stationary frame-work whose lower portion or base 6, is provided with a step-box 7, in which is journaled the lower extremity of a vertically disposed shaft 8; the upper extremity, or this shaft is journaled at 9 in a stationary

beam 10. Below the beam 10 the shaft is provided with a pulley 12 with which is connected an operating belt 13 leading to a line-shaft or any suitable motor for imparting a relatively rapid movement to the shaft. Upon this shaft is mounted a cam 14. The body of this cam may be termed frusto-conical in shape, while upon two opposite sides of this cone-shaped structure cam members 15 are formed. (See Fig. 1.) The eccentricity of these cam members is greatest at the top of the cam and diminishes downwardly therefrom so that the bottom of the cam body is circular, the cam members having diminished to zero at the bottom of the cam body. This cam is mounted to rotate with the shaft but is splined thereon, whereby it is vertically slideable as shown in the drawing (see Fig. 3). The shaft is provided with two splines or feathers 16 which engage counterpart grooves formed in the cam. This cam is adjusted vertically by means of two screw shafts 17 whose lower extremities are journaled in the cam and whose upper extremities engage threaded openings formed in a collar 18 made fast upon the shaft 8. Each screw shaft is provided with a centrally located enlargement 19 provided with openings 20 for the insertion of a hand spike or other device to facilitate the operation of the screws. Mounted above the base 6 of the stationary frame, is a rotary platform 21, upon which are mounted a suitable number of uprights 22 and 23. These uprights 22 and 23 are arranged in pairs, the uprights 22 being outermost or farther from the center of motion. Upon top of the various pairs of uprights 22 and 23 is mounted a launder 24 which is of undulatory or zig-zag shape. This launder is divided into two circular compartments 25 and 26 separated by a vertically disposed circumferential partition 27. The launder 24 receives its supply from a stationary launder 28 provided with depending discharge pipes or nozzles 29. Mounted upon the uprights 22 and 23, each of which is double being composed of two substantially twin members, are upper and lower radially disposed bars 30. These bars are pivotally connected with the uprights 23 by means of bolts 31. Other bolts 32 connect the bars with the uprights 22 which are provided with slots 33 to permit the adjustment of the bars whereby they may be arranged at different inclinations for a purpose hereinafter apparent. When these bars have been properly adjusted, they are secured by tightening the bolts 31. Each bar 30 is double being composed of two members whose outer portions 34 diverge from the radial direction, and are provided with rollers 35 which form an anti-frictional support for the concentrating

tables 36 which are provided with side arms 37 resting upon the said rollers. These arms 37 on opposite sides of the table are parallel but their inner portions 38 are bent inwardly toward each other, their inner extremities being pivotally connected as shown at 39, with radially disposed rods 40 mounted to reciprocate in stationary uprights 41 and 42. Mounted upon each rod 40, is a coil spring 43, one extremity of which bears against the outer upright 41, while the other engages a collar 44 which is adjustable on the rod by means of a set bolt 45, to regulate the normal tension of the spring. The inner extremity of each rod 40 is bent downwardly as shown at 46 and upon this downwardly bent portion, is rotatably mounted a disk or roller 47 which engages the operating cam 14, hereinbefore described. Upon the inner uprights 42 is mounted a circular casing 48 having a bottom 49 whose central portion is provided with an opening 50 through which the operating shaft 8 passes. The shaft is loose in the casing 48 and also in the platform 41. The bottom of the latter is provided with a bearing 51 which is secured to the platform by cap screws 52 passing through flanges 53 formed on the top of the bearing, the lower portion of the bearing being provided with flanges 54 engaging bearing balls 55 which engage upper and lower grooves formed in the flanges 54 and in the step-box 7, respectively.

It must be understood that while the shaft 100 and the platform 21 together with its super-structure, both rotate, the movement of the shaft is relatively rapid, thus necessitating that it loosely engage the platform, and casing 28.

As shown in the drawing the structure consists of two series or decks of tables 36, one deck being arranged directly above the other. In this event the arms 37 of each pair of tables, the members of which are arranged one above another, are connected with a pair of arms 38 which approach each other as they extend inwardly from the tables, the four arms 38 being connected with the outer extremity of each rod 40. As is illustrated in the drawing, the upper and lower arms 38 on each side of the rod 40 are formed integral with each other. From this explanation it will be understood that each pair of tables composed of an upper and a lower table member reciprocates in unison. The inner extremity of each of these tables is provided with a depression 56. The extreme end of the table beyond this depression is provided with an adjustable plate 57 connected with the table by a bolt 58. By raising or lowering this plate, the upward movement of the coarser concentrates, in order to escape from the inner extremity of the table, may be regulated. In other

words, the adjustment of this plate determines the depth of the accumulation of concentrates within the depression 56. The pulp to be treated upon the tables, is fed thereto by means of depending conduits 59 and 60, the conduits 59 supplying the lower deck and the conduits 60 the upper deck of tables. The lower extremities of these conduits are connected with curved plates 61 by means of fastening devices 62. These plates are supported between the side arms 37 of the tables and are curved to discharge the pulp upon the inner extremity of the body of the table; they are located immediately above the table depressions 56 and serve to prevent the pulp from entering these depressions before it passes to the body of the table. The conduit 59 leads from the inner compartment 26 of the launder 24, while conduit 60 leads from the outer compartment of the said launder.

It must be understood that a feed pipe 59 leads to each table 36 of the lower deck, while a feed pipe 60 leads to each table 36 of the upper deck of tables. Furthermore, each of these conduits leads from the lowest part 63 of each portion or section 64 of the launder 24. Each of these launder portions 64 is composed of a bottom which is downwardly inclined in both directions, thus making it practicable to remove the entire contents of the launder by the use of the conduits 59 and 60. Attention is called to the fact that the upper stationary launder 28 is provided with a partition which separates the same into a pulp compartment and a water compartment. The location of this partition is indicated at 65 (see Fig. 1). As this view is really a section taken below the launder 28 it is impracticable to show the partition in the launder but its location is indicated thereon and this is all that is thought necessary. This launder is also provided with another partition whose location is indicated at 66 in Fig. 1 and a third partition whose location is indicated at 67.

Assuming that the rotary structure is traveling in the direction indicated by the arrow in Fig. 1, it must be understood that the stationary launder 28 is so constructed that it delivers pulp to the tables while they are traveling underneath the portion of the launder extending in the direction indicated by the arrow, from the partition 67 to the partition 65. While the tables are passing underneath the portion of the launder from the partition 65 in the direction indicated to the partition 66, wash water is fed to the tables, while from the partition 66 to the partition 67 there is no discharge from the launder to the tables, since while they are passing from one of these partitions to the other, concentrates are removed from the tables through the action of the spray pipes 68 and 69. The spray pipe 68 is supplied

with water from a conduit 70 having a valve 71; while the spray pipe 69 is supplied with water from a conduit 72 having a valve 73. The spray pipe 68 is of such length as to cover only the outer portion of the table from which the middlings are washed. It is assumed, after the wash water has been delivered to the tables from the launder 28, that the outer portion of the table will contain some mineral values that are not entirely clean. These I term middlings, and it is the function of the water from the spray pipe 68 to wash these middlings from the tables into a trough 74 having an outlet 75. After these middlings are removed the remaining material upon the table consists of pure concentrates and is washed therefrom by the spray pipe 69 into a trough or receptacle 76 having a discharge outlet 77. When the structure is in operation a relatively slow movement is imparted to the platform 21 and the superstructure mounted thereon, by a cable 78 which engages a groove 79 formed in the periphery of the platform which is circular in shape. This cable engages guide pulleys 80 located adjacent an operating pulley 81 fast upon a vertically disposed shaft 82. The operating cable passes around the pulley 81. The shaft 82 and this pulley are rotated by a belt 83 engaging a pulley 84 also fast on the shaft 82. This belt 83 may lead from a line-shaft or other suitable operating device or motor not shown.

When the machine is in operation the platform 21 and the tables mounted thereon rotate at a relatively low speed or travel slowly, while the shaft 8 and the operating cam mounted thereon is supposed to rotate rapidly at a speed considerably greater than that of the tables. Hence it is immaterial whether or not the tables rotate in the same direction as the shaft 8 since the difference in speed will be sufficient to make it practicable to impart to the tables the required differential motion through the medium of the cam 14 and the actuating springs 43. It will be understood that during the operation of the machine, the outer stroke of the longitudinal reciprocating or vibratory movement is imparted to the tables by the cam members 15, while the return movement is imparted by the springs 43 which are placed under tension during the outward stroke of the tables. This cam together with the actuating springs is so constructed and arranged that the reciprocating vibration imparted to the tables through their combined agency, serves to stratify the slimes upon the top of the table which is supposed to be covered with canvas or other suitable woven or plush material adapted to answer the purpose. At the same time this differential movement is such that the heavier or coarse concentrates, if the

pulp should contain the latter, are caused to travel rearwardly upon the tables and discharge into the depressions 56 at the inner extremity of each table.

5 From what has already been stated it will be understood that the tables, assuming that they are traveling in the direction indicated by the arrow in Fig. 1, will receive pulp from the launder 24 while traveling from the partition 67 to the partition 65; while traveling from the partition 65 to partition 66, they will receive wash water; and finally while traveling from the partition 66 to the partition 67 the table 10 will receive nothing from the launder since during this interval the middlings and pure concentrates are washed from the tables through the agency of the spray pipes 68 and 69 as heretofore explained. The elements just referred to as partitions 67, 65 and 66 may rather be considered as positions than partitions, since in Fig. 1 the concrete structures cannot be illustrated. In this view, however, the inner and outer dotted circles A and B designate the portions of the launder 28. During the operation of the structure it will be understood that during the stratification of the slimes upon the tables and the saving of the heavier mineral values by causing them to travel inwardly, and lodge in the depressions 56 at the inner extremity of the tables, the gangue travels outwardly upon the tables and is discharged into a lower launder 85. 15 The centrifugal force due to the rotary action of the structure, aids in the separation and discharge of the gangue.

Attention is called to the fact that by virtue of the special construction of the cam 14, whereby the eccentricity of the cam members 15 varies, the differential motion imparted to the tables may be varied in quality to adapt them for use with various grades or kind of material. As shown in the drawing; a trough or receptacle 86 is mounted upon the rotary platform and located in position to catch the coarse concentrates as they are discharged from the depressions 56 at the inner extremities of 20 the various tables.

Upon the bars 30 are mounted plates 87 which close the spaces between the tables 36 and prevent the possible escape of pulp or water between the tables during the operation of the machine.

Having thus described my invention what I claim is:

1. A concentrator comprising a series of tables arranged in circular form, and centrally located rotary means for simultaneously imparting a differential outward motion to the tables, said means including

a vertically adjustable cam provided with cam members on opposite sides and whose eccentricity varies in a vertical direction, 65 whereby the adjustment of the cam varies the quality of the differential movement, for the purpose set forth.

2. A concentrating apparatus comprising a series of concentrating tables radially arranged, means for imparting a differential reciprocating motion to the tables consisting of a centrally located rotatable cam provided with cam members on opposite sides and whose eccentricity varies in a vertical direction, 70 radially disposed rods connected with one extremity of the tables and engaging the surface of the cam whereby motion is imparted to the tables in an outward direction, tension springs mounted on the rods whereby motion is imparted to the tables in an inward direction, and means for adjusting the cam whereby the reciprocation of the tables is varied, substantially as described.

3. A concentrating apparatus comprising upper and lower decks of tables arranged in circular form, guide members upon which the said tables are slidably mounted, means for imparting a reciprocating motion to the said tables, comprising a centrally located rotatable cam mounted upon an operating shaft, the said cam being provided with cam members on opposite sides, and whose eccentricity varies in a vertical direction; 90 radially arranged rods connected with the tables and engaging the surface of the said cam, means for holding the rods in engagement with the surface of the rotatable cam, the said cam being vertically adjustable 100 upon the operating shaft whereby the reciprocating motion of the tables may be varied, substantially as described.

4. A concentrating apparatus comprising a plurality of decks of tables arranged in circular series, means for rotating all of the tables, and a centrally located, rotatable and adjustable cone-shaped member provided with cam members on opposite sides, whose eccentricity varies in a vertical direction, 105 for simultaneously imparting motion to all of the tables of the several decks in an outward direction, the corresponding table sections of the different decks being connected to a common actuating means adapted to 110 be actuated by said cam members, substantially as described.

In testimony whereof I affix my signature in presence of two witnesses.

WILTON E. DARROW.
